COMBINED VALVE AND SWITCH
MECHANISM

Samuel Helfand, Erie, Pa.

Application January 28, 1931, Serial No. 511,817

8 Claims. (Cl. 200—53)

As exemplified the invention is applied to an ordinary gas range. These ranges present a real hazard in the ordinary household in that the valves as ordinarily located are within easy reach of children so that it is not uncommon for children operating the gas valves to turn on the gas which may result in serious damage. The invention involves the arrangement of the control in position where it cannot be readily handled by children and also in a position where it may be more readily controlled by the operator. The invention also contemplates a unitary control for a plurality of burners and an automatic lighting system so that as the gas is turned on for any burner the burner is automatically lighted. Other features and details of the invention will appear from the specification and claims.

A preferred embodiment of the invention is illustrated in the accompanying drawings as follows:

Fig. 1 shows a perspective view of the stove with the apparatus in place thereon.

Fig. 2 a front view of the control mechanism with parts removed and partly in section.

Fig. 3 a plan view of a spring for seating the valve for seating the valve plugs.

Fig. 4 a central section through the control mechanism on the line 4—4 in Fig. 2.

Fig. 5 a section on the line 5—5 in Fig. 4.

Fig. 1 marks the stove frame. This has four burner openings 2 of the ordinary domestic range, and an elevated oven 1a for convenience. A control 3 for the burners is mounted on the top of the oven.

Gas is supplied to the burners from a manifold 4. The manifold has a manifold chamber 5 and a supply pipe 6 leads into the manifold preferably at the axis of the manifold. The gas passes from the chamber 5 through radial openings, or ports 7 to valve chambers 7a. Valve plugs 8 are arranged in the chambers, each plug having a port 9 adapted to be brought into register with the opening 7 and an axial port 10 leading through the smaller end of the plug to a discharge opening 11. A pipe 12 leads from each discharge opening to a mixer 13 of a burner 14, there being as many valves around the manifold and as many pipes as there are burners. A cap 15 is arranged over the manifold chamber. A spring 16 is se-

cured on the cap by a cap screw 17. This spring engages shoulders 18 on the valve plugs 8, the single spring, therefore, exerting pressure on all the plugs, thus maintaining the plugs in close seating engagement with the chamber walls.

The valve plugs are provided with the usual

stop pins 19 operating in slots 20 in the walls of the chamber, thus limiting the movement of the valve plugs to positions bringing the ports 9 into register with the ports 7 and into a position closing said ports. A key mounting 21 is rotatively mounted on a screw 22 extending from the cap screw 17. A key 23 is adapted to be inserted into a key socket 24 in the outer end of each of the valve plugs. The key 23 has an extension 23a which extends into a stem 25. The stem extends through a guide shoulder 26 and a spring 27 is seated on the guide shoulder and operates against a shoulder 28 on the stem, thus normally retracting the key 23. A shoulder 29 on the key engages the inner surface of the guide shoulder 26 and limits the outward movement of the key and stem. A handle 30 is arranged on the outer end of the stem.

The operator in turning on the gas for any desired burner grasps the handle 30, swings the mounting 21 with the key into position over the particular valve plug controlling the burner to which it is desired to admit gas. The handle is then pushed inwardly carrying the key into the socket 24 and the valve plug is operated turning on the gas and the key released. The key is then free to be used with relation to other valve plugs, if desired, and the gas is turned off by bringing the key again into position and into the socket and returning the plug to closed position. In this manner a convenient control may be arranged operating for all the burners and may be placed at a point of safety so far as children are concerned.

I prefer to provide the mechanism with a lighting device so that as the gas is turned on to any burner, the burner is automatically lighted. This is much simplified with the present mechanism in that the key used is automatically retracted after the gas is turned on so that this inward and outward movement of the key may be utilized for closing the switch of an electric lighter. A bridge plate 31 is mounted upon the shoulder 29 of the key, but insulated therefrom by insulation 32. This bridge plate presses in between spring switch fingers 33 when the key is forced inwardly to operative position, as clearly shown in dotted lines in Fig. 5. The switch fingers are secured to, but insulated from the sides of the valve chamber by screws 34. Wires 35 lead to and from the switch fingers and to and from one side of a transformer 36 stepping down the current from the main supply wires 37. The wires 35 pass to a spark coil 38 operating a spark plug 39, the points 40 being in igniting position relatively to the burner.

There is a lighting device with a similar switch for each valve chamber so that when the key is brought over any valve for any burner and forced inwardly to actuate the valve it closes the electric circuit so that as the gas is turned on a spark is provided for immediately igniting the gas.

What I claim as new is:—

1. In a combined valve and switch mechanism, the combination of a conduit; a rotatable valve controlling the conduit; means actuating the valve including a key; a mounting for the key in which the key is movable axially to and from engagement with the valve; and a switch controlled by the axial movement of the key.
- 15 2. In a combined valve and switch mechanism, the combination of a conduit; a manifold to which the conduit leads; rotative valve connections leading from the manifold; valves controlling the connections; a key for the valves; a mounting for the key in which the key is axially movable into and out of engagement with the valves, said mounting housing the valves being movable to guide the key relatively to the valves; switches, one for each valve; and means operating the switch with the axial movement of the key as each valve is opened.
- 20 3. In a combined valve and switch mechanism, the combination of a conduit; a manifold to which the conduit leads; connections leading from the manifold; rotative valves controlling the connections, said valves being similarly spaced about a common center; a key for the valves; a rotative mounting for the key in which the key is axially movable into and out of engagement with the valves, said mounting rotating to guide the key selectively to the valves, said mounting having an axis at the common center; switches, one for each valve; and means closing the switches with the opening of each valve.
- 25 4. In a combined valve and switch mechanism, the combination of a conduit; a manifold to which the conduit leads; connections from the manifold; valves controlling the connections; a key for the valves; a mounting for the key in which the key is axially movable into and out of engagement with the valves, said mounting housing the valves and rotating to guide the key selectively to the

valves; and a switch closed by the movement of the key to engage a valve.

5. In a combined valve and switch mechanism, the combination of a conduit; a manifold to which the conduit leads; connections leading from the manifold; valves controlling the connections, said valves being similarly spaced about a common center; a key for the valves; a rotative mounting for the key in which the key is axially movable into and out of engagement with the valves, said mounting rotating to guide the key selectively to the valves, said mounting having an axis at the common center; and a switch closed by the movement of the key to engage a valve the mounting forming a housing for the switches.

6. In a combined valve and switch mechanism, the combination of a conduit; a manifold to which the conduit leads; connections leading from the manifold; valves controlling the connections, said valves being similarly spaced around a common center; a key for the valves; a rotative mounting for the key adapted to guide the key selectively to the valves, said mounting having an axis at the common center; a common spring centrally supported acting on all the valves for seating them; and a common device securing the mounting and the spring.

7. In a combined valve and switch mechanism, the combination of a conduit; a rotatable valve controlling the conduit; means actuating the valve including a key; a mounting for the valve in which the key is moved axially to and from engagement with the valve; a switch controlled by the axial movement of the key; and a spring automatically returning the key and opening the switch when the key is released.

8. In a combined valve and switch mechanism, the combination of a conduit; a manifold to which the conduit leads; a plurality of rotative valves mounted concentrically around the manifold; connections leading from the valves; a key for the valves; and a mounting for the key in which the key is movable axially into and out of engagement with the selected valve, said mounting being movable to guide the key selectively to the valves and forming a housing for the valves.

SAMUEL HELFAND.
